SINGLE CRANE GIRDER

Misumi Osawa, Tokyo-to, Japan, assignor to Ishikawa-jima-Harima Jukogyo Kabushiki Kaisha, Tokyo-to, Japan, a company of Japan

Filed Apr. 2, 1965, Ser. No. 445,134

Claims priority, application Japan, Oct. 22, 1964
(utility model), 39/82,825
6 Claims. (Cl. 212—17)

This invention relates to lifting cranes and more particularly to a single crane girder.

Single crane girders of the conventional type are so constructed as to include the following elements, a trolley with a vertical wheel *e* and horizontal wheels *f*, *g* around the girder *a*, rails *b*, *c*, *d*, having been laid, respectively, for the upper vertical wheel *e* along the upper chord of the box-shaped girder *a*, for the upper horizontal wheel *f* along another chord of the girder *a*, and for the lower wheel *g* along the lower chord of the girder *a*.

A single girder of the conventional type with the aforementioned construction, however, tends to be too heavy, because a platform for an electricity-feeding apparatus must be provided independently, since the entire upper length *h* of the girder *a* cannot be used. This is a result of a trolley astride the width *l* of the girder *a*, and also because the girder *a* must be made strong enough to bear torsional loading.

The present invention discloses a single girder, the upper surface of which can be used effectively and whose weight is reduced. The girder comprises a beam which can bear the horizontal wheel pressure from the downward vertical wheel of the trolley, and also absorbs the horizontal wheel pressure from the lower horizontal wheel of the trolley. The downward vertical wheel is located at the web of said girder.

The present invention will be more clearly understood from the following description of specific embodiments of the invention together with the accompanying drawings:

FIGS. 1-3 show preferred structures of single crane girders of the present invention. FIG. 4 shows the disposition of dashboards in a single crane girder of the present invention. FIG. 5 shows the structure of a single crane girder of the conventional type.

FIG. 1 shows an embodiment in which a beam 3 having an H-shaped cross-section is installed on the extension of web 2 of girder 1, which has a box-shaped cross-section. Vertical wheel 5 and upper horizontal wheel 6 of trolley 19 move along said beam 3.

FIG. 2 shows an embodiment in which a beam 4 having a cross-section of box-shape, one side of which is a portion of upper chord 7 of the girder, is utilized. Vertical wheel 5 and upper horizontal wheel 6 move along said beam 4. Slant brace 17 is disposed to bear possible torsion in the horizontal direction.

FIG. 3 shows an embodiment in which upper horizontal wheel 6 moves above upper chord 7 by having an extension of web 2 of girder 1 upward from upper chord 7, and installing a piece of steel, member 8, for fixing a rail 10 for upper horizontal wheel 6 on the web-side end of upper chord 7. Vertical wheel 5 moves immediately above web 2 by installing a piece of steel member 9, to which is fixed rail 11. Upper horizontal wheel 6 moves on rail 18 which is secured to steel member 8. The cross-section of the girder is a closed section, the inside of the girder 1 and the inside of the beam formed by the upper end of the web 2 and the steel members 8 and 9 being open to each other.

FIG. 4 shows a rail 12 for the lower horizontal wheel 13. Dashboard 14 is installed in various places in order

2

to make beams 3 and 4 lock with each other. Saddles 18 are located at both ends of the beam.

In the case of the single crane girder of the present invention, in which various rails are concentrated around web 2 of girder 1, the upper space of girder 1 is used effectively by making the trolley smaller, thereby enabling the upper space to be used for a platform for electricity-feeding apparatus. In the present invention, there is no need to provide an independent platform as in the case of the girder of the conventional type. Furthermore, lighter material can be used, as it is made possible to decrease the strength of the structure for girder 1 as compared with that of the girder of the conventional type, the torsion being borne by beams 3 or 4. A reduction of expense is also made possible.

In the case of the single crane girder shown in FIG. 3, in which various rails are concentrated around web 2 of girder 1, the trolley can be made smaller and the upper space of the girder can be effectively used. Furthermore, as the torsion can be borne by the beam formed by the upper part of web 2 and steel members 8 and 9, the weight of the girder 1 can be made lighter. These merits are present in the embodiments shown in FIG. 1 and FIG. 2. In addition, since the cross-section of the girder is a closed section, dashboard 14, being a single construction, can be inserted easily and precisely, and the shear stream can be calculated very easily. Rails 10 and 11 are easily affixed by welding or bolting even after the girder has been built up.

In the case of the girder shown in FIGS. 1 and 2, the girder may be so constructed as to bear torsion in vertical planes by welding dashboards 14 on the upper chord 7 and beams 3 and 4, or by installing a slant brace. While the embodiment shown in FIG. 3 does not illustrate a direct structural connection between chord 7 and web 2, a user of this invention is not precluded from adding such a connection in the form of cutting and welding struts or gussets to said parts at a later time.

What I claim is:

1. A single crane girder for use with a trolley comprising: a girder having an upper and a lower chord; a beam supported by said girder and disposed along a portion of the topmost portion thereof, said beam comprising a plurality of members disposed above said upper chord, said members forming at least one substantially horizontal bearing surface and at least one substantially vertical bearing surface, strengthening means disposed above said upper chord and connecting said members; rail means disposed on said bearing surfaces and on a lower portion of said girder forming means for sustaining pressure from the wheels of a trolley and that the width of said upper chord exceeds by a substantial amount the combined width of said beam, said horizontal bearing surface and the horizontally disposed wheel contacting said horizontal bearing surface.

2. A single crane girder according to claim 1 wherein said beam is substantially box-shaped.

3. A single crane girder according to claim 1 wherein said strengthening means comprise a portion of a web of said girder.

4. A single crane girder according to claim 1 wherein said strengthening means comprise a diagonal member.

5. A single crane girder according to claim 1 wherein said strengthening means comprise a portion of said upper chord.

6. A single crane girder for use with a trolley comprising: a girder having an upper and a lower chord and a web; a beam supported by said girder and disposed along a portion of the topmost portion thereof, said beam comprising a plurality of members disposed above said upper

chord, said members forming at least one substantially horizontal bearing surface and at least one substantially vertical bearing surface, a portion of said web extending above said upper chord and connecting said members; rail means disposed on said bearing surfaces and on a lower portion of said girder forming means for sustaining pressure from the wheels of a trolley and that the width of said upper chord exceeds by a substantial amount the combined width of said beam, said horizontal bearing surface and the horizontally disposed wheel contacting said horizontal bearing surface.
